US00D838085S

(12) United States Design Patent (10) Patent No.: US D838,085 S
(45) Date of Patent: * Jan. 15, 2019

(54) DOUBLE SEAM YOKE

- (71) Applicant: THE H.D. LEE COMPANY, INC.,
Wilmington, DE (US)
- (72) Inventors: Darren J. Peshek, Irvine, CA (US);
Justin T. Mark, Irvine, CA (US);
Brian Marion, Irvine, CA (US); Kyle
Stephens, Irvine, CA (US); Donald
Hoffman, Irvine, CA (US); Stephen H.
Zades, Greensboro, NC (US); Varun
Wadhawan, Kwun Tong (HK)
- (73) Assignee: THE H.D. LEE COMPANY, INC.,
Wilmington, DE (US)
- () Term: 15 Years
- (21) Appl. No.: 29/611,350
- (22) Filed: Jul. 20, 2017
- (51) LOC (11) Cl. 02-02
- (52) U.S. Cl. D2/742
- (58) Field of Classification Search

Assistant Examiner — J. Thorn, Sr.

(74) Attorney, Agent, or Firm — Baker & Hostetler LLP

(57) CLAIM

The ornamental design for a double seam yoke, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front view of a double seam yoke lying flat showing a new design.

FIG. 2 is a back view of a double seam yoke lying flat showing a new design.

FIG. 3 is a left side view of a double seam yoke lying flat showing a new design.

FIG. 4 is a right side view of a double seam yoke lying flat showing a new design.

FIG. 5 is a top view of a double seam yoke lying flat showing a new design.

FIG. 6 is a bottom view of a double seam yoke lying flat showing a new design.

FIG. 7 is a perspective right front view of a double seam yoke as worn showing a new design; and,

FIG. 8 is a rear view of a double seam yoke as worn showing a new design.

The dashed lines showing the pants and other details on the pants forms no part of the claimed design.

1 Claim, 6 Drawing Sheets
